US0D1014902S

(12) **United States Design Patent** (10) **Patent No.:** **US D1,014,902 S**
(45) **Date of Patent:** **** Feb. 13, 2024**

(54) **INTELLIGENT DELIVERY LOCKER**

(71) Applicant: **Agora Networks Oy**, Espoo (FI)

(72) Inventor: **Saku Sysiö**, Espoo (FI)

(**) Term: **15 Years**

(21) Appl. No.: **35/513,692**

(22) Filed: **Sep. 10, 2021**

(80) **Hague Agreement Data**

Int. Filing Date: **Sep. 10, 2021**

Int. Reg. No.: **DM/218986**

Int. Reg. Date: **Sep. 10, 2021**

Int. Reg. Pub. Date: **Feb. 25, 2022**

(30) **Foreign Application Priority Data**

Mar. 11, 2021 (EM) 008458897-0001

(51) **LOC (14) Cl.** **03-01**

(52) **U.S. Cl.**

USPC **D99/31**; D14/307; D6/664

Primary Examiner — Kathleen L Jones

(57) **CLAIM**

The ornamental design for an intelligent delivery locker, as shown and described.

DESCRIPTION

FIG. 1.1 is a front-right perspective view of the intelligent delivery locker;

FIG. 1.2 is a rear-left perspective view of the intelligent delivery locker;

FIG. 1.3 is a rear-right perspective view of the intelligent delivery locker;

FIG. 1.4 is a front-left perspective view of the intelligent delivery locker;

FIG. 1.5 is a left view of the intelligent delivery locker;

FIG. 1.6 is a right view of the intelligent delivery locker; and

FIG. 1.7 is a rear view of the intelligent delivery locker. Broken lines depict surface treatment and other portions of the intelligent delivery locker forming no part of the claimed design; unshaded surfaces adjacent broken lines form no part of the claimed design.

1 Claim, 7 Drawing Sheets
